UNITED STATES PATENT OFFICE.

ELOY RODRIGUEZ, OF FAJARDO, PORTO RICO.

OIL-BURNER.

1,359,747.

Specification of Letters Patent. Patented Nov. 23, 1920.

Application filed October 25, 1919. Serial No. 333,392.

To all whom it may concern:

Be it known that I, ELOY RODRIGUEZ, a citizen of the United States of America, residing at Fajardo, Porto Rico, have invented certain new and useful Improvements in Oil-Burners, of which the following is a specification.

The present invention has reference to burners adapted to be used with liquid fuel, such as crude oil.

With burners of this nature it is often difficult to produce an efficient combustion owing to the fact that the liquid does not readily atomize and also that the fuel nozzle becomes clogged with an accumulation of solid material contained in the oil.

One of the objects of this invention is to provide a burner in which the liquid fuel prior to its discharge to be atomized by the action of steam whereby the cold oil will be prevented from overflowing the nozzle in consequence of which leakage will be prevented and a constant pressure and efficient flame obtained.

Another object of my invention is to construct the burner so that thick oil when used as fuel on entering the burner will be broken up into small particles so that its flow through the burner will be continuous.

Another object of this invention is to provide a burner which can be readily cleaned without removing the burner and disconnecting it from the oil and steam supply pipes.

It is a further object of my invention to provide such a construction which will enable its application to any kind of boiler furnaces, either marine or land.

And still a further object is to construct the fuel burner of but a few parts thereby greatly simplifying and cheapening the burner.

With these and other objects in view, my invention consists in the combination, construction and arrangement of parts as hereinafter more fully described and set forth in the appended claims.

In the accompanying drawing in which similar reference characters denote corresponding parts, Figure 1 is a sectional view of the oil burner; Fig. 2 is a longitudinal section on line 2—2 of Fig. 1; Fig. 3 is a cross section on line 3—3 of Fig. 1; Fig. 4 is a front view of the oil burner with a part broken out; Fig. 5 is a front view of an intermediate section of the oil burner; Fig.

6 is a similar view as Fig. 1 of a somewhat modified construction; Fig. 7 is a similar section as Fig. 2 of this modified construction; Fig. 8 is a front view thereof and Fig. 9 is a longitudinal section of the front part of the burner.

Referring specifically to the drawing, and first to the construction shown in Figs. 1—5, the oil burner is composed of several sections to wit: 1, 2, 3, and 4, which are removably jointed together so that for cleaning or other purposes the sections can be easily taken apart without disconnecting the device from the supply pipes. As will be seen from the drawing the base portion or section 1 of the burner is provided with two lateral threaded bores 1¹ 1² extending longitudinally through the body and parallel to one another. The bore 1¹ serves for the attachment of the supply pipe for steam and terminates in a substantially Z-shaped groove which is complemented by a similar groove provided in the intermediate section 2 to form a substantially conical steam pocket 1³. This pocket leads into a circular passage 2¹ made in the intermediate disk shaped section 2 and owing to its shape is adapted to gradually compress the steam before the latter passes into the chamber 3¹. The bore 1² serves for the attachment of the supply pipe (not shown) for crude oil and terminates in a passage 1⁴ leading into a cylindrically curved chamber 2². The chamber 2² extends laterally from said passages 1⁴ and its walls are so shaped as to form an obstruction *a* whereby the oil flowing into the chamber through the oil inlet will be deflected from its course and thereby retarded, in consequence of which the oil contained in the chamber will be more effectively heated.

The section 3 is funnel shaped or in form of a truncated cone, and is formed with a central cylindrical chamber 3¹ into which the steam is allowed to accumulate through the central passage 2¹ from the supply pipe leading into the passage 1³. Extending through the section 3 are a plurality of longitudinal passages 3² of circular cross section which are arranged close to one another and which lead from the bottom of the wall opposite the inlet 1² of the chamber 2² or are arranged in such relation to said wall that the oil flowing into said oil chamber will be deflected from its straight course by said wall and prevented thereby from passing

direct into the oil passages. The passages 3² are separated by a comparatively thin wall from the steam chamber 3¹ so that the steam accumulating in the latter will heat 5 the oil flowing through the passages 3² and maintain it in liquid state.

The chamber 3¹ and passages 3² do not extend to the front end of the section 3 but terminate inside said body. The chamber 10 3¹ is closed by a convex dome 3³. Just beyond the said dome 3³ a segment of the section 3 is cut away so that the base of said segment 15 is a horizontal plane about even with the longitudinal center line of the chamber 3¹ of said segment and the rear wall thereof is a vertical plane coinciding with the top or front wall of the dome 3³ and the front open ends of the passages 3². Cut transversely in said wall 3³ is a horizontal slot 3⁴ which 20 constitutes the egress or mouth of the chamber 3¹. In the horizontal wall 3⁷ a groove 3⁹ is provided the lateral walls 3¹² of which diverge forwardly from the corners of the mouth 3⁴ (Fig. 2).

25 The segmental portion cut away from the body 3 forms the section 4 of the four sections composing the burner. This segmental section 4 is provided with a groove 4¹ at its bottom surface and at its rear with a groove 4², so that when the parts are assembled the groove 4¹ forms with the groove 3⁹ the nozzle n, and the groove 4² forms a duct for the oil leading into said nozzle.

30 The mouth opening 3⁴ is partly obstructed by a member 5 which is countersunk in the front wall 3⁶ of the section 3 and by screw bolts 6 is secured to the latter. The lower end or lip 5¹ of the member is curved forwardly projecting into the nozzle n. The section 4 is removably secured to section 3 by screw bolts 7 or other suitable means.

To hold the different sections together I provide the following construction:

45 The base portion 1 is formed with diametrically opposed eyes 1⁶ each provided with a threaded bore 1⁷. The body or section 3 has at its rear end an annular enlargement forming a shoulder 3¹⁰. Cylindrical sleeves 8 each formed at one end with a lateral projection or nose 8¹ serve as clamp members. The latter are adapted to be placed against the eyes 1⁶ and to engage with their noses 8¹ the shoulder 3¹⁰. Loosely 50 borne in the sleeves 8 are bolts 9 which at one end are threaded as at 9¹ and adapted to work in the threaded bores 1⁷ of the eyes 1⁶, and at their opposite ends are formed with heads 9² to abut against the front faces 55 of the sleeves 8. By screwing the bolts 9 into the threaded bores 1⁷ of the eyes the clamping sleeves 8 will firmly join the sections 1 and 3 with the intermediate section 2 compressed between them.

60 65 To reproduce a tight joint between the

sections 1, 2 and 3 and to guard section 2 against displacement, section 2 is provided on its rear and front faces with grooves 2³, 2⁴, adapted to engage annular flanges 1⁵ and 3⁵ formed on the sections 1 and 3 respectively. 70

The mode of operation of my burner is as follows:

After the sections of the burner have been properly assembled and the burner is positioned in the furnace of the locomotive or the like, the supply pipes (not shown) are screwed into the bores 1¹ and 1². Steam flowing through pipe 1¹ accumulates in the steam chamber 3¹ and heats the oil which accumulates in the chamber 2² and thence passes into the different passages 3². While flowing through the latter the oil is continuously heated by the steam contained in the chamber 3¹ and is thereby maintained in liquid state. Emerging from the chamber 3¹ through the mouth 3⁴ the steam is thrown upwardly by the wall 3⁷ and unites with the oil emerging from the passages 3² and flowing down the passage 4¹ whereby the fuel particles will be broken up and become atomized before it passes outwardly through the nozzle n. At the same time the steam shooting through the nozzle n will remove any foreign body accumulating in the nozzle n and prevent thereby the clogging of the latter. 85 90 95

The above described burner is adapted for use on small locomotives or the like.

For bigger locomotives I prefer to employ 100 the construction shown in Figs. 6-9, which in principle is the same as the first described burners, but differs from the latter aside from size also in certain particulars to be presently described.

105 In this modification the burner is composed of five sections instead of four, to wit, the base a, an intermediate disk shaped section b, a cylindrical section c, a conical head d and a segment shaped section e. The sections a, b and c are joined together by screw bolts f instead of by the clamps used in the first described construction. The front end c¹ of the cylindrical section c is somewhat reduced in diameter and screw threaded 110 and adapted to be screwed into a threaded bore d¹ of the conical head d. 115

120 The oil passages g arranged in an arc around the steam chamber h provided in the cylindrical section c in front terminate in ducts or passages d² provided in the head piece d and lead into a common passage i formed by the segment e. The tongue j which is arranged in front of the slot or mouth h¹ of the steam chamber and whereby the quantity of steam issuing from the chamber and passing into the nozzle n is 125 adjustably secured to the head d by providing it with oblong holes j¹ through which the fastening screws k are passed. By rais- 130

ing or lowering the tongue *j* the passage between the lip *j* of the tongue *j* can be increased or reduced.

The operation of this modified burner is 5 the same as that of the first described construction.

The advantage of my burner construction over those hitherto in use, is, as already stated, that it permits the burner to be readily 10 taken apart without requiring its disconnection from the supply pipes and its removal from the furnace.

The divisional lines of the different sections are so selected that the passages and 15 chambers therein when the sections are taken apart are accessible for cleaning, and inspection as to the cause of interruption of the flow of the fuel when this occurs.

What I claim is:

20 1. An oil burner for locomotives or the like comprising a body formed with oil and steam inlets, a central comparatively large steam chamber in which at one end the steam inlet terminates and having at its opposite end a slot like discharge or mouth, a plurality of oil passages extending longitudinally over the entire length of said chamber and around an upper part of the latter, a nozzle leading from said mouth, an adjustable tongue in front of said discharge having a bent portion extending into said nozzle, said adjustable tongue serving to control the flow of steam from said mouth into said nozzle, and a duct leading from 30 said oil passages downwardly into said nozzle and forming a mixing chamber in which the steam emerging from the mouth under said tongue while rising is caused to mix with the downwardly flowing oil and 35 atomizes it.

2. In an oil burner, an oil chamber, an inlet leading into one end of the rear wall of said chamber, a plurality of comparatively narrow passages leading from the opposite 45 wall of said chamber and extending laterally from said oil inlet, said chamber being so shaped as to form an obstruction in front of said oil inlet which obstruction will cause the oil flowing into said oil chamber 50 to be deflected, thereby causing the oil contained in the said chamber to become effectively heated.

3. An oil burner having a steam chamber, a plurality of comparatively narrow passages above and around said chamber, steam and oil inlets and a separable breaker plate between said oil passages and said oil inlet, said plate being formed with a chamber having an obstructed passage in which said 60 oil inlet terminates.

4. An oil burner having a steam chamber, a plurality of comparatively narrow oil passages above and around said chamber, steam and oil inlets and a separable plate between 65 said oil passages and oil inlet formed with

an oil chamber communicating on one side with said oil inlet and on the opposite side with said oil passages, said chamber being so shaped and located relative to said oil inlet as to form an obstruction adapted to deflect 70 the flow of the oil entering said chamber from said oil inlet and thereby permitting the oil contained in said chamber to become effectively heated.

5. An oil burner, having a steam chamber 75 formed with a slot shaped discharge or mouth, a plurality of comparatively narrow oil passages above and around said chamber, a nozzle in extension of said mouth having an outlet conforming in shape with 80 that of the latter, said nozzle having a removable section, an exchangeable member in front of said mouth to control the flow of steam from the latter, said removable section being adapted to inclose said member 85 and having a groove forming a channel or duct in which the front ends of said oil passages terminate and the lower part of which forms a chamber in which the steam emerging from underneath said exchangeable member is caused to mix with the 90 downwardly flowing oil and atomizes it.

6. An oil burner, having a steam chamber, a plurality of oil passages, oil and steam inlets and a separable section between said 95 chamber and passages on one side and said inlets on the other side, said separable section being formed with a steam pocket.

7. A liquid fuel burner having a chamber 100 to contain a heating medium, a plurality of passages for the liquid fuel, inlets for the liquid fuel and for the heating medium and a separable section between said chamber and passages on one side and said inlets on the other side, said separable section having a fuel chamber formed with an obstructed passage in which the fuel inlet terminates and which fuel chamber is capable 105 of being heated by the heating medium contained in said first named chamber.

8. A liquid fuel burner having a chamber for a heating medium and formed with a discharge or mouth, a plurality of comparatively narrow passages for the liquid fuel around said chamber, a nozzle in extension 115 of said mouth having a removable section, an exchangeable member in front of said mouth to control the flow of the heated medium from the latter, said removable section being adapted to inclose said member 120 and having a groove forming a channel in which the front ends of said fuel passages terminate and the lower part of which forms a chamber in which the heating medium emerging from underneath said exchangeable member mixes with the downwardly flowing liquid fuel and atomizes it.

9. A liquid fuel burner for locomotives or the like, comprising a body formed with inlets for the liquid fuel and for a heating 125

medium, a chamber for said heating medium in which the inlet for the latter terminates and which has a discharge or mouth, a plurality of passages for the liquid fuel extending around said chamber, a nozzle leading from said mouth, an adjustable member in front of said mouth serving to control the flow of the heating medium from said mouth into said nozzle, said nozzle 10 having a duct leading from said fuel passages downwardly and forming a mixing

chamber in which the heating medium emerging from the mouth under said adjustable member while rising is caused to mix with the downwardly flowing liquid fuel 15 and atomizes it.

In testimony whereof I affix my signature in presence of two witnesses.

ELOY RODRIGUEZ.
